Atty.

UNITED STATES PATENT OFFICE.

HERBERT J. SAUVAGE, OF CHICAGO, ILLINOIS, ASSIGNOR TO TRUSTEES OF THE ELECTRO THERMOSTATIC CONTROL COMPANY, OF CHICAGO, ILLINOIS, A TRUST ESTATE.

THERMOSTATIC ELECTRIC SWITCH.

Application filed January 31, 1927. Serial No. 164,761.

My invention relates to electric-switches thermostatically or temperature controlled, with suitable means for varying the adjustment thereof, whereby the switch will be 5 operated at different prevailing temperatures.

More specifically, the appliance may be set to work at one temperature during the day and at another temperature during the 10 night, an appropriately-constructed clock automatically shifting or regulating the temperature-controlling means, at least in part.

To enable those skilled in this art to fully understand the invention and the numerous 15 advantages accruing from its employment, in the accompanying drawings, forming a part of this specification, a present, preferred embodiment of the invention has been depicted in detail, and, for simplicity, 20 like reference characters have been employed for the same parts throughout the several views.

In these drawings,—

Fig. 1 is a face view or front elevation of 25 the complete appliance;

Fig. 2 is a longitudinal section, on an enlarged scale, through the casing or housing of the structure, with the clock omitted and with some portions of the structure in 30 section;

Fig. 3 is a fragmentary view of the upper portion of the construction as shown in Fig. 2, with the parts in different positions;

Fig. 4 is a partial, longitudinal, vertical 35 section through the appliance, on line 4—4 of Fig. 1, and on an enlarged scale;

Fig. 5 is a fragmentary section on line 5—5 of Fig. 4; and

Fig. 6 is a horizontal section on line 6—6 40 of Fig. 2.

By reference to these drawings, it will be noted that the device includes a base-plate 11 of the general form of the perimeter of the illustration in Fig. 2.

45 Mounted on this main support or back plate, by suitable screws or otherwise, there is another supporting plate 12, of irregular shape or form, having a forwardly-projecting, horizontal ledge or shelf 13, on which 50 the lower end wall of a hollow bellows-member 14 is fixedly mounted.

Such member 14 is within a movable yoke 15, against the upper, inner wall of which the top end or head of the bellows-member

bears, so that as the latter expands, under 55 the influence of heat, it will carry the yoke upwardly, as will be readily understood, the extent of upward travel of the yoke being limited by the lower wall thereof coming into contact with the under surface of the 60 support 13.

The yoke at its top is supplied with an upstanding lug or finger 16 designed and adapted to co-operate with a split, metallic saddle 17 fulcrumed on the plate 12 at 18 65 and having a hollow glass-vessel 19 fixedly clamped therein and oscillatory or rockable therewith, such part 19 having a pair of internal electric-contacts 21 and 22 connected outside of the oscillatory glass-member with 70 properly-insulated, electric conductors or leads 23 and 24, a small body of mercury 25 within the glass-vessel being adapted to make and break the contact between the terminals 21 and 22 as the vessel 19 is rocked 75 in the one direction or the other.

Inasmuch as this electric-switch is hingedly mounted or fulcrumed at one side of its center of gravity, it tends to rock down, if permitted to do so by the bellows 80 member, so that the mercury makes the contact between the two terminals, but as the bellows member expands the vessel will be tilted in the opposite direction, causing the mercury to flow down quickly away from, 85 and hence breaking its connection with, the pair of contacts.

A coiled, contractile spring 26 is connected to the lower portion of the movable yoke at 27, and at its bottom end it is connected to a nut 28 carrying on its outer face an index plate 29 adapted to display temperature numerals, according to the adjustments of the parts, through the window or opening 31 in the front wall of the casing 90 or housing 32, the latter, for convenience, being also supplied with a glass thermometer 33 on its outer face.

To prevent the nut 28 from turning and to keep the plate 29 properly positioned, 100 they are provided with a rearwardly-extended arm or plate 34, the rear end of which travels in and is guided by an upright slot of the proper width in the plate 12.

A screw-threaded shaft 35 extends through the threaded opening of the nut 28, and its cylindrical, reduced-diameter part 36 is capable of turning in a bearing 37 properly

mounted in a forwardly-projecting bracket-portion 38 of the plate 12, the lower end of such screw member 35, 36 having below the bottom of the housing 32 a knurled head or 5 finger piece 39 by means of which the screw may be turned to adjust the tension of the spring 26 and thus vary the temperature at which the electric-switch will be operated.

At each of its vertical sides the yoke 15 10 is supplied with a coiled spring 41, the lower end of which is secured to a nut 42 adjustable by a screw 43 carried by the yoke, the nut being prevented from turning by reason of overlapping the upper and lower margins 15 of the corresponding portion of the yoke.

At its upper end, each such spring is connected at 44 to a lever 45 fulcrumed on the top of the yoke at 46 and projecting outwardly beyond the spring, as shown in 20 Fig. 2.

The two springs 41 tend to pull their two levers or arms 45 downwardly, the movements of such members in this direction being limited by cross pins 40, 40 connecting 25 together parts of the yoke-frame.

It will be apparent, therefore, that when such parts 45 bear on the pins 40 by reason of the action of their springs 41, the latter perform no otherwise useful function.

30 These two springs, however, are provided for the purpose, under certain circumstances, of counteracting in part the downward pulling action of the spring 26 on the yoke so that the thermostatic element 14 will operate 35 the switch; that is, open the electric circuit, at a lower temperature than when the spring 26 exerts its full strength on the yoke, the springs 41 being then inoperative.

In order that such supplemental or auxiliary springs 41 may be thrown into and out 40 of action, the following co-operating instrumentalities have been provided:

The plate 12 has forwardly-projecting, parallel flanges 47, 47 along its upright 45 margins, and between and guided by these I provide a vertically-slidable frame 48 having a pair of outstanding lugs or fingers 49, 49 below and adapted to co-operate with and lift the pair of hinged arms or levers 45, 45 50 under certain conditions.

Such slidable frame 48 is yieldingly pulled downwardly by a small spring 51 connected thereto at 52 and joined to a pin 53 mounted on the plate 12.

55 The upper end of the element 48 is connected by a link 54 to the short arm of a bell-crank lever 55 fulcrumed on the plate 12 at the point 56, the end of the long arm of the part 55 having a pin 57 which projects forwardly and also rearwardly from the member 55, such latter portion of the pin being located in a slot in the bell-crank lever 58, fulcrumed on the base-plate 11 at 59 and having an extension or finger piece 61 extended outwardly through a slot in the cir-

cular housing 60 at the top part of the appliance and adapted to demountably accommodate a clock 68.

A three-armed lever 62, 63, 64 is fulcrumed at 65, the arm 62 having a lug 66, the arm 63 having a notch 67 adapted to co-operate with the pin 57, and the arm 64 extending outwardly through a slot in the casing 60.

Any suitable form of spring 70 is associated with this multi-arm lever tending to 75 rock it in a clockwise direction, its extent of movement being limited, however, by the pin 57, which either occupies the notch 67 or is directly below the lower edge of the arm 63, which rests thereon as presented 80 in Fig. 3.

A shaft of the clock 68, at its rear face, carries a cam-disk 69 angularly adjustable on the shaft to vary its time or moment of operative action, the shaft making one complete revolution for each twenty-four hours. The cam projection 71 of disk 69 is positioned and adapted to co-operate with the lug or finger 66, and, during the movement 90 of the cam 69 in a clockwise direction, rocking the three-armed lever in a counter-clockwise way.

We will assume that it is desired to have the temperature controlled so that the room in which the appliance is mounted will be 95 heated, by the heating mechanism controlled by the thermostatic electric-switch, and maintained at a temperature of seventy degrees during the daytime and at a temperature of fifty degrees during the night.

Accordingly, during the daytime the parts will occupy the position shown in Fig. 3 corresponding to the inactive condition of the springs 41, because then the frame 48 is in its lowered relation.

The full tension of the spring 26 is then operative on the yoke and the associated bellows-member, so that it requires a greater pressure within the part 14, which accommodates any suitable volatile material, to rock 110 the electric-switch to open the circuit controlling the heating mechanism.

When evening arrives and it is desired to have the temperature lowered, the clock is wound up and its cam mechanism set for the desired time of release, the disk 69 then occupying the position presented in Fig. 2.

The arm 58 is shifted upwardly, by its finger piece 61, from the position shown in Fig. 3 to that indicated in Fig. 2, the pin 57 being received in the notch 67, so that the arm 58 is maintained locked in this elevated relation, it being obvious that the lug 66 is in the path of travel of the cam-projection 71.

The upward movement of arm 58 shifts the frame 48 upwardly and carries the fingers 49 in the same direction, their upward travel lifting the arms or levers 45 off of their pins 40, so that the parts 49 constitute

fixed abutments for the upper ends of the two springs 41, which thereupon exert a united lifting action on the yoke 15, which is less, however, than the downward pull of the spring 48 on the yoke.

Stated somewhat differently, the springs 41 in this condition neutralize the action of spring 46 in part, so that the bellows member can expand more readily and open the 10 electric-switch at the lower temperature of fifty degrees.

This condition will continue until the cam projection 71 rocks the lever 62, 63, 64 in a counter-clockwise direction, releasing the 15 pin 57 and permitting the frame 48 and its fingers 49 to descend under the downward pulling action of the spring 51, thereby again restoring the springs 41 to inactive condition by reason of the movement of the 20 fingers 49 downwardly away from the arms or levers 45.

From then on the appliance will operate automatically to maintain a temperature of seventy degrees until the device is again 25 reset to cause a temperature of fifty degrees to prevail, all as will be readily understood.

The invention is not limited and restricted to the precise and exact details of structure presented, and these may be modified more 30 or less radically without departure from the principles of the invention, the latter being defined by the appended claims.

I claim:

1. The combination of a thermostatic 35 bellows-member, an electric-switch actuated by said member, a spring resisting action of said member, means adapted to counteract in part the action of said spring, and means to render said counteracting means operative and inoperative.

2. The combination of a thermostatic bellows-member, an electric-switch actuated by said member, a spring resisting action of said member, spring means adapted to 45 counteract in part the action of said spring, and means to render said spring means operative and inoperative.

3. The combination of a thermostatic

bellows-member, an electric-switch actuated by said member, a spring resisting the expanding action of said member, means adapted to counteract in part the action of said spring, manual means to render said counteracting means operative, and clock-operated means to restore said counteracting means to inoperative condition.

4. The combination of a thermostatic bellows-member, an electric-switch actuated by said member, a spring resisting the expanding action of said member, spring 60 means adapted to counteract in part the action of said spring, manual means to render said counteracting spring means operative, and clock-operated means to restore said counteracting spring means to inoperative condition.

5. The combination of a yoke, a thermostatic bellows-member in and operating said yoke, an electric-switch actuated by the movements of said yoke, a spring resisting 70 the movements of said yoke occasioned by the expansion of said bellows-member, spring means adapted to act on said yoke in opposition to the action of said spring thereon, manual means to render said spring 75 means operative, and clock-operated means to restore said spring means to inoperative condition at a predetermined adjustable time.

6. The combination of a yoke, a thermostatic bellows-member in and operating said yoke, an electric-switch actuated by the movements of said yoke, a spring resisting the movements of said yoke due to the expansion of said bellows-member, spring means 85 adapted to act on said yoke in opposition to the action of said spring thereon, manual means to hold said spring means operative against its tendency to return to inoperative condition, means to lock said manual 90 means with said spring means in such operative condition, and clock-operated means to release said lock.

In witness whereof I have hereunto set my hand.

HERBERT J. SAUVAGE.
